UNITED STATES PATENT OFFICE.

HARRY E. LE ROY, OF COLUMBIA, PENNSYLVANIA.

FLYING DART.

1,115,078.

Specification of Letters Patent. Patented Oct. 27, 1914.

Application filed April 16, 1914. Serial No. 832,317.

To all whom it may concern:

Be it known that I, HARRY E. LE ROY, a citizen of the United States, residing at Columbia, in the county of Lancaster and State of Pennsylvania, have invented a new and useful Flying Dart, of which the following is a specification.

The present invention relates to improvements in flying darts, and more particularly to that class of device which constitutes a toy aeroplane, one object of the invention, being the construction of a device which when propelled in any desired angle upwardly into the air, will glide a comparatively great distance, the same being preferably thrown manually into the air as high as possible to be permitted to glide in any direction that it may assume.

With the foregoing and other objects in view which will appear as the description proceeds, the invention resides in the combination and arrangement of parts and in the details of construction hereinafter described, and claimed, it being understood that changes in the precise embodiment of the invention herein disclosed can be made within the scope of what is claimed without departing from the spirit of the invention.

In the drawings Figure 1 is a side elevation of the complete dart. Fig. 2 is a top plan view thereof. Fig. 3 is a front elevation thereof. Fig. 4 is a view in elevation of the stick and cord used for throwing the dart.

Referring to the drawings, the numeral 1 designates the main longitudinal member of the dart, which is provided with the blunt forward end 2 and with the tapered end 3 terminating in the fin or tail 4, which is also tapered in cross section and as particularly shown in Fig. 3. Attached to the upper face of the member 1 adjacent the end 2 thereof is a semi-circular plane member 5, the curved end of which is toward the front end of the dart. Connected to the under side intermediate of the member 1 by means of a metal strip 6 which is disposed longitudinally below the member 1, is the wing section 7, which is of peculiar shape as shown in Fig. 2 and extends upon opposite sides of the member 1.

In order to assist in throwing the present dart to the desired height, the stick 8, with the heavy handle end 9 and the reduced end 10 carrying a cord or flexible connection 11 55 is provided.

What is claimed is:

1. A flying dart, comprising a longitudinal member slightly tapered in cross section from its forward end toward the rear 60 end, a tapered tail member formed upon the reduced end of the longitudinal member, a guiding plane attached to the upper surface adjacent the butt or enlarged end of the longitudinal member, and a wing member 65 attached to the under side intermediate of the ends of the longitudinal member.

2. A flying dart, comprising a longitudinal member, rectangular in cross section and having a blunt nose, said member being tapered toward the tail end with a blade member formed integral with the tail member and projecting above and below the longitudinal member, a semi-circular guiding plane attached to the upper surface of the 75 longitudinal member adjacent the nose end thereof, and a wing member attached to the under side intermediate of the ends of the longitudinal member.

3. A flying dart, comprising a longitudinal member, rectangular in cross section and having a blunt nose, said member being tapered toward the tail end with a blade member formed integral with the tail member and projecting above and below the 85 longitudinal member, a semi-circular guiding plane attached to the upper surface of the longitudinal member adjacent the nose end thereof, a wing member, and a metal strip attached to the under side of the longitudinal member and intermediate of the ends of the wing member for securing the wing member to the longitudinal member.

In testimony that I claim the foregoing as my own, I have hereto affixed my signature 95 in the presence of two witnesses.

HARRY E. LE ROY.
